UNITED STATES PATENT OFFICE

FRANK H. ORDNER, OF BUFFALO, NEW YORK; FLORA M. ORDNER ADMINISTRATRIX
OF SAID FRANK H. ORDNER, DECEASED.

STRAIGHTWAY VALVE.

1,055,215.

Specification of Letters Patent.

Patented Mar. 4, 1913.

Application filed January 23, 1909. Serial No. 473,924.

To all whom it may concern:

Be it known that I, FRANK H. ORDNER, a citizen of the United States, and a resident of Buffalo, county of Erie, and State 5 of New York, have invented certain new and useful Improvements in Straightway Valves, of which the following is a full, clear, and exact description.

My invention relates to improvements in 10 valves and more particularly to straight way valves and it is especially designed to take the place of gate valves.

I have sought to produce a valve which would have a perfect seat and at the same 15 time be easily and quickly opened. With this and other objects in view I have produced my invention and it provides a valve which is quick to open, has a perfect seat and is so constructed that no matter what pressure 20 may be exerted against it, it can not leak nor creep. Moreover the edges of the valve seat cannot be ground by sand or other grinding substances found in water since the valve seat is always kept clear and free from 25 grinding sediment by the flow of the first and last water which passes the valve and its said seat.

My valve possesses not only the advantages above enumerated, but it is simple in 30 construction and cheap to build.

Those skilled in the art will easily understand from the following description and the accompanying drawings the many advantages which result from the use of my 35 invention.

Referring now to the drawings: Figure 1 is a sectional elevation of my invention. Fig. 2 is a section taken on the line $x-x$ of Fig. 1.

40 8 represents the usual valve casing somewhat changed in form to adapt itself to my valve.

4 is the inlet conducting pipe and 5 the outlet conducting pipe both of which are 45 provided as shown with the usual screw threads for uniting it to additional lengths of pipe.

The spindle standard 6 at its lower end seats upon the upper part of the valve casing 3 and this seat may be ground to a tight fit if so desired. A collar 7 provided with a right angled top flange 8 is screwthreaded as shown to the upper part of the valve casing 3 and the right angled flange 8 fits upon

a shoulder of the lower end of the spindle 55 standard 6 thus holding firmly together in a tight joint the said spindle standard 6 and the valve casing 3.

The spindle 9 is preferably provided with screw threads 10 and 11 one of which is 60 preferably a right handed screw and the other a left handed screw. The screw threads 10 mesh with the screw threads in the spindle standard 6 as clearly shown. The screw threads 11 mesh with screw 65 threads 12 in my wedge block 13. The spindle 9 passes through the spindle standard 6 and into the said wedge block 13.

A screwthreaded cap 14 fits over the top of the spindle standard 6 and the spindle 9 70 passes through its center. The usual packing means 15 are provided for keeping the joint formed between the cap 14 and the spindle standard 6. To the top of the spindle 9 is suitably secured in the usual manner the hand wheel 16 or any other suitable means for rotating the spindle 9.

The wedge block 13 is adapted when held in its lowermost position as clearly shown in full lines in Fig. 1 to press against the 80 swing valve 17. This swing valve 17 is pivotally mounted upon a pin 18 suitably located in the valve casing 3. The swing valve is adapted to rotate from the position shown in full lines in Fig. 1 to that shown 95 in dotted lines in that figure.

On the face of the swing valve 17 which contacts with the wedge block 13, I provide a guide flange 19 which is adapted to travel in a suitable groove 20 in the wedge 90 block 13. The function of this guide flange and groove is to keep the swing valve 17 in its proper line of travel when it moves upon its pivot pin 18 and likewise to keep it properly seated when it closes the porthole 95 into the pipe 4.

A pin 21 is suitably secured at one end in the guide flange 19 and is provided at its opposite end with a contact hook or flange 22. A groove is provided in the wedge 100 block 13 to allow the pin 21 to rest loosely therein and allow the wedge block to rise until it comes in contact with the flange 22 on the said pin when the further rise of the wedge block will pull the swing valve 17 105 upwardly and away from the porthole of the pipe 4. Thus positive means are provided for pulling the swing valve away

from its seat but of course the swing valve may be pushed away therefrom by pressure.

On opposite sides of the valve casing 3 I provide guideways 23 and 24 in which side flanges 25 and 26 provided on each side of the wedge block 13 are adapted to travel. The function of the guideways 23 and 24 and the side flanges 25 and 26 is to keep the wedge block 13 in a straight line of travel when it is moving upwardly or downwardly.

The operation of my valve is as follows: When the valve is seated the parts occupy the positions shown in full lines in Fig. 1. 15 When it is desired to open the valve the hand wheel 16 is revolved and the right handed threads 10 and the left handed threads 11 on the spindle 9 operate to produce a quick upward travel of the wedge block 13. As soon as the wedge block 13 begins to rise it releases its pressure against the guide flange 19 of the swing valve 17 and the pressure of water in the pipe 4 may then be exerted to push the swing valve 20 17 from its seat. If this pressure is not sufficient to push the swing valve 17 from its seat then as soon as the wedge block 13 is raised sufficiently far to come in contact with the flange 22 of the pin 21 the upward motion of the wedge block 13 will pull the swing valve 17 away from its seat and when the wedge block 13 has reached the uppermost limit of its travel the swing valve 17 30 will be in the position shown in dotted lines in Fig. 1, and will be held there by means of the pin 21. Reversing the rotation of the hand wheel 16 will quickly drive the wedge block 13 downwardly and this will simultaneously drive the swing valve 17 35 downwardly until the wedge block 13 and the swing valve 17 are in the position shown in full lines in Fig. 1. 40

Obviously when the wedge block 13 is in its lowest position it presses very hard against the swing valve 17 and holds it firmly against its seat. By reason of the guideways 23 and 24 and the guide flanges 25 and 26 it will be clear that the spindle 9 and the wedge block 13 are held in their proper vertical position and no side strain is put upon the spindle 9 by reason of any pressure which may be exerted in the pipe 4 against the swing valve 17.

The seat of the swing valve 17 will obviously be kept clean of any sediment which would grind the seat by reason of the fact that the first flow of water over the seat tends to keep it clean and the last flow of water which is allowed to pass the seat likewise washes it clean of any sediment. The pressure of the wedge block 13 against the guide flange 19 is always sufficient to keep the swing valve 17 firmly on its seat and produce a tight fit.

65 Obviously it is not an essential part of

my invention that the screw threads on the spindle shall be one right handed and the other left handed since they may both be either left or right handed, but when of the character shown and herein described, they will produce a quicker travel upwardly and downwardly of the wedge block and therefore a quicker opening of the swing valve. It is not essential that the swing valve 17 should be mounted as herein shown, the only essential being that the said valve be made to move away from and onto its seat simultaneously with the upward and downward movement of the wedge block and further that it be held firmly on its seat by the wedge block.

What I claim is:

1. The combination of a valve casing provided with a valve seat, guide ways provided within said casing, a valve pivoted within said casing, a valve controlling member longitudinally movable in said guide ways, link connections from said valve controlling member to said valve to swing the latter on its pivot and means to actuate the valve controlling member. 85 90

2. In a straight way valve the combination with the valve casing, the valve handle and the valve spindle of a swing valve rotatably mounted in said valve casing, a wedge block screwthreaded to said valve spindle and adapted to hold said swing valve on its seat when in its downward position and release said swing valve from its seat when in its upward position, a pin secured to said swing valve and a hook flange on the upper end of said pin whereby when said wedge block is drawn upwardly it contacts with said hook flange and thereby draws upward said swing valve.

3. In a straight way valve, the combination with a valve casing, a valve handle and its spindle, of a swing valve rotatably mounted in said valve casing, a guide flange on the face of said swing valve, a wedge block secured to said spindle and provided with a guide groove in which said guide flange is adapted to travel, a pin secured to said swing valve and a hook flange on the upper end of said pin whereby when said wedge block is drawn upwardly it contacts with said hook flange and thereby draws upwardly said swing valve. 115

4. In a straight way valve, the combination with a valve casing, a valve handle and its spindle, of a swing valve mounted in said valve casing, a guide flange on the face of said swing valve, a wedge block movable vertically in said valve casing, provided with a guide groove and screw-threaded to said valve spindle, a pin secured to said swing valve, a hook flange on the upper end of said pin whereby when said wedge block is drawn upwardly it contacts with said hook flange and thereby draws upwardly 130

said swing valve, and means for guiding the vertical travel of said wedge block in said valve casing.

5. The combination of a valve casing provided with a valve seat, longitudinal guide ways provided within said casing, a valve pivoted within said casing and provided with a wedge surface, a valve controlling member longitudinally movable within said 10 guide ways and provided with a wedge surface, means connecting said controlling member with said valve to swing the same from its seat and means to actuate said controlling member, whereby the wedge surface 15 on the said controlling member will co-act with the wedge surface on the said valve to force the same to its seat.
6. The combination of a valve casing provided with a valve seat, longitudinal guide 20 ways provided within said casing, a valve pivoted within said casing and provided with a wedge surface, a valve controlling

member longitudinally movable within said guide ways and provided with a wedge surface, loose link connection between said controlling member and said valve to swing the same from its seat and means to actuate said controlling member, whereby the wedge surface on the said controlling member will co-act with the wedge surface on the said 25 30 valve to force the same to its seat.

7. The combination of a valve casing provided with a valve seat, a valve pivoted in the casing, a valve controlling member movable in the casing and loose link connections 35 therefrom to the valve to swing the same on its pivot, and means to actuate the valve controlling member.

In testimony whereof I have hereunto set my hand in the presence of two witnesses. 40

FRANK H. ORDNER.
